Attorney.

UNITED STATES PATENT OFFICE.

WILLIAM L. LIGHTFORD, OF INDIANAPOLIS, INDIANA.

THROTTLING VAPORIZER FOR HYDROCARBON ENGINES.

Application filed December 23, 1923. Serial No. 683,155.

To all whom it may concern:

Be it known that I, WILLIAM L. LIGHTFORD, a citizen of the United States, residing at Indianapolis, in the county of Marion and State of Indiana, have invented a new and useful Throttling Vaporizer for Hydrocarbon Engines, of which the following is a specification.

My invention relates to an improvement 10 in a throttling vaporizer for hydrocarbon engines and it is the purpose of my invention to provide means whereby a vaporizer may be applied to any hydrocarbon engine such that the vaporizer will not interfere 15 with the carburation and control of the engine at any speed.

It is well known that many devices have been developed for the purpose of introducing an aqueous vapor into the combustible 20 mixture just prior to the admission of the mixture to the combustion chamber of the engine, and it has been determined that such a vapor produces so improved an action of the engine that any device for successfully introducing the vapor into the engine intake meets a popular demand. However, it has been developed that such vaporizers as have been heretofore produced are 25 primarily effective at a constant speed only, such that should the speed be changed, the air introduced into the engine intake from the vaporizer device materially affects the hydrocarbon-air mixture coming from the carburetor, and a resulting mixture too lean 30 or too rich for combustion at the particular new speed is produced, that can not be overcome by the flexibility of the carburetor.

Such a result leads to a loss of power, or 40 waste of fuel, and more seriously, either a stalling of the engine or poor acceleration—an action of great objection and handicap in such an engine as the varying speed engine of the automobile.

With the improvement I have conceived 45 constituting my invention, I have succeeded in devising means whereby vapor is not only introduced into the engine intake automatically only when the engine is at a proper working temperature, but its flow into the engine intake is regulated according to the engine speed and the consequent carburetor requirements. With my invention, the engine may idle or be quickly accelerated without the vapor introduction interfering with

the carburation; vapor is introduced into the engine only when the proper temperature is reached; the engine may be warmed up before the vaporizer comes into action; no vaporizing means other than the usual 60 radiator is required; no adjustments of my device are required to compensate weather fluctuations; and the installation is easily and readily made to any engine, particularly in the automotive field. My invention comprises few parts, is free of complication and is produced at a low cost.

I accomplish these and other objects as may hereinafter appear by the means as illustrated in the accompanying drawing, in 70 which—

Fig. 1 is a top plan view of my throttling vaporizer; Fig. 2 is the same view as in Fig. 1, with the top cover removed to show the thermostatic control; Fig. 3 is a vertical section taken on the line 3—3 of Fig. 2; and Fig. 4 is a view showing my vaporizer attached to an engine and one method of connecting it to the radiator overflow pipe, the intake manifold, and the carburetor control.

Like characters of reference indicate like parts throughout the several views.

My vaporizer is comprised primarily of a rectangular box-shaped body 5 having a 85 boss 6 in one end on which is firmly seated and secured a bi-metal thermostatic arm 7 by means of the screw 8, as indicated in Figs. 2 and 3. The arm 7 has one corner cut off to fit snugly against the triangular 90 raised portion 6' such that the arm may be assembled in the body in one way only to insure the arm having the proper metal upward to cause an increase in temperature 95 to produce an upward bending effect in the arm 7.

On the opposite under side of the body 5 is the depending nipple 9 having the internal vertical passage 10, the valve seat 11 at the upper end of the passage 10, and the 100 enlargement of the passage 10 above the valve seat to receive with a loose fit the valve plug 12, with its depending stem 13 adapted by its conical end to seat on the seat 11 and so close the passage 10. Extending 105 laterally from the nipple 9 is the nipple 14 having an internal passage 15 discharging into the enlarged section of the passage 10.

The free end of the arm 7 is bifurcated and engages in the annular groove 16 of 110

the valve plug 12, as shown in Figs. 2 and 3, such that the valve plug is normally held down by the arm 7 to cause the stem 13 to close the passage 10.

5 The body 5 is enclosed by the cover 17 held in position by battering over the edge of the body at points as at 18. Extending up through an opening in the cover 17 is the valve plug head 19. Pivotaly mounted on 10 the pin 20 supported by the arm 21 extended from the body 5 is the rocker 22 having the arms 23 and 24. The arm 23 is pressed on the valve plug head 19 by means of the coil spring 25 which has the end 26 hooked over 15 the arm 23 and its other end 27 bearing against the body 5. A stud 28 fits loosely through an eye in the outer end of the arm 24. The stud is formed with the eye 29 and the shoulders 30 and is adjustably secured to 20 the arm 24 by the nut 31 and the lock nut 32.

The body 5 is provided with a bracket 33 by means of which the body is attached to some convenient point on the engine 46, Fig. 4, such as by means of the manifold cap 25 screw 34. To the nipple 14 is attached the tube 35 by the union nut 36, which tube connects with the overflow pipe 37 of the radiator 38. A tube 39 leads from the depending nipple 9 into the intake manifold 45, 30 such manifold being the manifold leading from the carburetor 40.

Rigidly mounted on the throttle shaft of the carburetor 40 is a bell crank having the arms 41 and 42. To the arm 41 is pivotally 35 secured the usual throttle rod 43, and to the arm 42, I pivotally secure one end of the rod 44 which has its other end pivotally secured to the stud 28 through its eye 29. The arm 24 is here shown curved to afford 40 clearance of the rod 44 behind the tube 35. While I have here shown one method of mounting the vaporizer body 5 and its connections will vary with the individual design of 45 the engine. It is preferably desired, however, to mount the body 5 on or closely adjacent to the exhaust manifold of the engine to afford a means of supplying the necessary 50 heat to operate the thermostatic arm 7.

An important feature of my invention is that the tension of the spring 25 be sufficiently great to hold the valve stem 13 on its seat in opposition to the lifting effect of the 55 arm 7 as the arm tends to spring upward when heated.

Assuming that the engine is cold on which 60 my vaporizer is installed, the engine is started in the customary manner and the throttle rod 43 is pushed forward, toward the carburetor, to open the throttle valve within the carburetor. As the rod 43 travels forward, the bell crank arm 42 pulls downward on the rod 44 such that the connected rocker 65 arm 23 is lifted from the valve head 19.

Should the engine still be cold, which would imply that the water in the radiator had not reached a temperature whereby any appreciable amount of vapor was passing off from the water, the arm 7 would remain in its 70 normal position and maintain a closed passageway to the engine intake manifold from the radiator overflow by keeping the valve plug stem on its seat 11. With continued 75 operation of the engine, the engine temperature rises correspondingly heating the arm 7 when the arm will start bending upward to lift the valve plug 12 to open the passage 10, such that the vacuum in the intake manifold 45 will cause a flow of air and vapor 80 from the radiator overflow pipe 37 through the tube 35, passage 15, around the valve stem 13, down through the passage 10, through the tube 39 and finally into the manifold 45. 85

When the engine speed is to be reduced the throttle rod 43 is pulled back and the interconnected parts cause the valve plug stem to be seated and close the passage 10, so stopping the admission of any air 90 as well as vapor into the engine intake manifold other than that entering through the carburetor. The distance between the shoulders 30 on the stud 28 and the under side of the nut 31 is slightly greater than 95 the thickness of the arm 24, to permit of idling speed adjustments, the take up of lost motion in the throttle rod and other connections, and to permit the spring to 100 seat the valve stem effectually.

Having fully described my invention in the form now best known to me, and as modifications may be made without departing from the spirit of the invention, I do not desire to be limited to the precise form as 105 shown any more than may be required by the following claims.

I claim:

1. In a vaporizer for hydrocarbon engines, the combination with an intake manifold, a radiator overflow pipe, and a carburetor throttle control, of means of thermostatically controlling the opening of a passageway from said radiator overflow pipe to said intake manifold, and means of controlling said thermostatic means operated in conjunction with said carburetor throttle control and normally resisting said thermostatic means.

2. In a vaporizer for hydrocarbon engines, the combination with an intake manifold, a radiator overflow pipe, and a carburetor throttle control, of thermostatic means of opening and closing a passageway from said radiator overflow pipe to said intake 125 manifold, said means comprising a bi-metal thermostatic arm fixed in a body by one end and engaging with the free end a valve plug intercepting said passageway within the body; and means secured to said carburetor 130

throttle control of preventing said thermostatic means from opening said passageway at low engine speeds.

3. In a vaporizer for hydrocarbon engines, the combination with an intake manifold, a radiator overflow pipe, and a carburetor throttle control, of thermostatic means of opening and closing a passageway from said radiator overflow pipe to said intake manifold, said means comprising a bi-metal thermostatic arm fixed in a body at one end, and a valve plug engaging with the free end of the thermostatic arm and intercepting said passageway within the body; a rocker arm adapted to seat said valve plug; means of seating said valve plug through said rocker arm and overcoming said thermostatic means; and means cooperating with the travel of said carburetor throttle control operating on said rocker arm to permit said thermostatic means to function at predetermined engine speeds and to prevent said thermostatic means from functioning at lower engine speeds.

4. In a vaporizer for hydrocarbon engines, the combination with an intake manifold, a radiator overflow pipe, and a carburetor throttle control, of thermostatic means of opening and closing a passageway from said radiator overflow pipe to said intake manifold, said means comprising a bi-metal thermostatic arm fixed in a body by one end and a valve plug engaging with the free end of the thermostatic arm and intercepting said passageway within the body; a rocker arm; a spring causing said rocker arm to bear on said valve plug with a pressure greater than that exerted by the thermostatic arm; and adjustable means connecting said carburetor throttle control with said rocker arm to permit a short travel of the said carburetor throttle control before causing a corresponding travel of the said rocker arm.

Signed at Indianapolis, county of Marion and State of Indiana, this 24th day of December, 1923.

WILLIAM L. LIGHTFORD.
